(57) **CLAIM**

The ornamental design for a cover for waterjet assembly, as shown and described.

DESCRIPTION

FIG. 1 is a front elevational view of a cover for waterjet assembly showing a first embodiment of our new design.

FIG. 2 is a rear perspective view thereof.

FIG. 3 is a left side elevational view thereof, the right side elevational view being symmetrical.

FIG. 4 is a rear elevational view thereof.

FIG. 5 is a top plan view thereof.

FIG. 6 is a bottom plan view thereof.

FIG. 7 is a front elevational view of a cover for waterjet assembly showing a second embodiment of our new design.

FIG. 8 is a rear perspective view thereof.

FIG. 9 is a left side elevational view thereof, the right side elevational view being symmetrical.

FIG. 10 is a rear elevational view thereof.

FIG. 11 is a top plan view thereof.

FIG. 12 is a bottom plan view thereof.

FIG. 13 is a front elevational view of a cover for waterjet assembly showing a third embodiment of our new design.

FIG. 14 is a left side elevational view thereof, the right side elevational view being symmetrical.

FIG. 15 is a rear elevational view thereof.

FIG. 16 is a top plan view thereof; and,

FIG. 17 is a bottom plan view thereof.

The broken lines in FIG. 15 are for illustrative purposes only and form no part of the claimed design.
